UNITED STATES PATENT OFFICE.

HEZEKIAH E. DEPP, OF SEDALIA, MISSOURI.

STREET-CAR PROPELLER.

SPECIFICATION forming part of Letters Patent No. 227,417, dated May 11, 1880.

Application filed October 18, 1879.

To all whom it may concern:

Be it known that I, HEZEKIAH E. DEPP, of Sedalia, in the county of Pettis and State of Missouri, have invented a new and useful Improvement in Street-Car Propellers, which improvement is fully described in the following specification and annexed drawings, in which—

Figure 1 is a side elevation of a street-car provided with my propelling device. Fig. 2 is a bottom view of the same.

The nature of my invention consists, first, in the combination, with a street-car or other wheeled vehicle, of cylinders for receiving mixed compressed air and steam, a compressed-air reservoir, a boiler for generating steam, and devices for mixing the steam and air outside the boiler, whereby air and steam mixed in close proximity to the working-cylinders and outside of the boiler can be employed for moving the vehicle; second, in the combination, with a street-car or other wheeled vehicle, of cylinders for receiving mixed compressed air and steam, a steam-boiler, a compressed-air reservoir, an air supplying and compressing pump having a steam-cylinder connected with it, and suitable devices for mixing the steam and air outside the boiler and in close proximity to the working-cylinders, as presently described; third, in a device whereby the exhaust of the air-compressor is utilized for aiding in propelling the car; fourth, in a device whereby air which is compressed in the cylinders of the propelling-engine, when this engine is reversed and before the car is stopped, is stored up and again utilized for aiding in propelling the car; fifth, in the combination of the aforesaid several devices for producing an improved mechanism for propelling cars or other vehicles with compressed air and steam combined, or with either compressed air or steam separately and in variable proportions, at the pleasure of the operator; sixth, in several combinations of pipes and cocks, hereinafter described and specifically claimed, whereby the supply of steam and compressed air is delivered, either separately or combined, to the working-cylinder of the air-pump and to the cylinders of the propelling mechanism, and whereby said supply can be regulated at pleasure.

In the drawings, A represents a car-body; B, the driving-wheels; C, a steam-boiler; D, a steam or air cylinder; E, an air-pump or air-compressor operated from the cylinder D, 55 and F F steam-cylinders for propelling the car.

The steam-boiler C is located on the front platform, and may be heated with any suitable fuel, the smoke of which escapes through a pipe, e.

A steam-pipe, c', leads from the boiler through the floor of the car toward the cylinder D, and near said cylinder unites with a pipe, g, which furnishes compressed air to the cylinder D from reservoir G, fastened below 60 the car on both sides. A cock, c², serves to cut off the steam-supply, and a cock, g', the air-supply, said cocks being operated from the front platform by means of hand-levers g² g³ and suitable connecting-rods. The contents 70 of one of the reservoirs G are confined by a stop-cock, g³, until the other reservoir is exhausted, whereupon the cock g³ is opened to continue the supply.

A pipe, c⁴, connected with the pipe c', conveys steam toward a suitable point opposite the cylinders F F, where it unites with two branches, c⁵, which are connected to the steam-chests of said cylinders. A stop-cock, c⁶, operated by a hand-lever, c⁷, on the platform of 80 the car, is provided on the pipe c⁴, for the purpose of letting on and shutting off the supply of steam for the cylinders F F.

The branch pipes c⁵ are, by means of a pipe, h, connected to a reservoir, H, which receives 85 the exhaust of the cylinder D by means of a pipe, d, which receives compressed air from the pump E by means of a pipe, e. Two pipes, E', are provided between the branches c⁵ and reservoir H, and have check-valves e', whereby 90 air is conducted from the branches to the reservoir, as will be explained.

A stop-cock, h', is provided on the pipe h, and between this cock and the branches c⁵ an air-friction device, I, similar to that patented 95 to me in 1878, is provided. The pipes E' are comparatively of much greater diameter than the passages in the device I, in order to allow the compressed air to freely pass into the reservoir H.

The stop-cock h' is operated from the front platform of the car by means of a hand-lever,

h^2 . The exhaust of the cylinders F is conducted by pipes f to an exhaust-tank, J, which is, by a pipe, j , connected with the air-supply pipe e^2 of the air-pump E. The piston-rods f' of the steam-cylinders F extend through both ends of the cylinders, and are secured in line by bearings f^2 fastened to the ends of the car. Opposite the driving-wheels B, which are provided with crank-pins b , the piston-rods f' are 10 provided with vertical yokes f^3 , in which the sliding bearings b' of the crank-pins move up and down.

The valve-rods f^4 of the steam-cylinders F are, by means of rocking shafts K, connected 15 with links L, which are operated by means of eccentric rods l and eccentrics M on the car-axles b' of the driving-wheels B. The links L are reversed by means of levers N on a shaft, n , and they are operated from the plat-20 form by a hand-lever, l' .

Operation: At the end station of the railroad the reservoirs G are charged with compressed air of considerable pressure—say three hundred and fifty pounds to the square inch.

25 The water of the boiler C is heated, and when steam of a suitable pressure is obtained the car is ready to start. The operator now opens the air-cock g' , whereby he sets the cylinder D and pump E in operation, thus filling the tank 30 H with compressed air. After a sufficient amount of compressed air is found to be in the tank H the operator opens first the steam-cock c^6 , and then the cock h' , whereby steam and air are admitted to the branches c^5 in op-35 posite directions, the air being with great force driven through the device I and brought to a high temperature by means of the device I, and in this state is mingled with the steam, and thus mixed steam and air is now con-40 ducted by the branches c^5 to the cylinders F, whereby the car is set in motion.

The exhaust of the cylinders F escapes by way of the pipes f to the tank J, which discharges it under a reduced pressure into the 45 air-supply pipe e^2 , by which it either passes to the air-pump E or out into the atmosphere. If the pump E is in action, the exhaust will pass into it, but if not in action will pass out at the open end of pipe e^2 .

50 When the car is to be temporarily stopped the operator reverses the propelling mechanism by means of the lever l' . The impetus of the car causes it to continue its forward motion for a while, whereby the cylinders F are 55 caused to draw out the contents of the tank J through the pipes f and to force them into the pipes c^5 , and thence through the pipes E' and check-valves e' into the tank H, for reuse. The car may again be started by moving the 60 links of the engine to one of their extreme positions.

By opening the cocks c^2 c^6 g' h' more or less the supply of compressed air and steam can be regulated to any desired proportion; and 65 by closing the cocks c^2 c^6 or the cocks g' h' the propelling or pumping mechanisms can be

worked either entirely by compressed air or by steam.

From the foregoing description and statement of operation of my invention it will be 70 seen that I have applied compressed-air reservoirs, a steam-engine, a steam-boiler, and an air-supplying pump upon the same supporting-frame, and combined with these an equalizing or air-pressure-reducing cylinder 75 and a working-tank; and, further, that the several parts are so constructed and provided with pipes, cocks, and adjuncts that the high pressure of the air in the reservoirs can be employed first for working the equalizing or 80 pressure-reducing cylinder D, and in this use of it it is caused to operate the pump E, and thereby force fresh or external air, by means of the open pipe e^2 , into the working-tank H, and simultaneously with this the exhaust-air 85 of the cylinder D will have become reduced in pressure from 350° to about 40°, which is the proper pressure for working the engines F F, and thus reduced it will enter the tank H, and from the tank H it passes to the point where 90 the steam is mixed with it. The steam flowing from the boiler mixes with the air, and the two enter the cylinders or engines F F, and thus the power for propelling the car is obtained.

In the event of the high-pressure air in the 95 reservoirs G G becoming exhausted to too great an extent, the steam can be used for assisting in working the pump, and the supply of air in the tank H can be augmented by drawing air into the pump E through pipe e^2 100 and forcing it into the tank H under a pressure equal to that in the reservoirs G G.

There is a great advantage in using the reservoirs G charged with air at a high pressure and then reducing the pressure, as described, 105 for by this means a very small boiler and furnace may be used, and the weight of the car will be greatly reduced. This, together with the provision made for keeping up a supply of compressed air in tank H for working the 110 engines with either a greater proportion of air than steam, or vice versa, or with steam alone or air alone, accordingly as circumstances require, renders my propeller well adapted for the special use of propelling street-cars and other wheeled vehicles, while it will 115 be found useful for driving machinery.

I claim—

1. In a propeller for street-cars, the combination of two cylinders, a boiler, and a compressed-air reservoir, whereby air and steam mixed outside the boiler are employed, substantially as and for the purpose set forth.

2. The combination with steam-cylinders, a steam-boiler, and compressed-air reservoir, of 125 an air-pump, E, and its cylinder D, whereby air and steam mixed outside the boiler are employed and atmospheric air is supplied to the apparatus during the travel of the car, substantially as and for the purpose set forth.

3. The combination of the cylinder D, exhaust-pipe d , and reservoir H, whereby the 130

exhaust-air and steam are stored for use in cylinders F in propelling the car, substantially as described.

4. The connecting-pipes E' and check-valves e' between the branches e⁵ and the tank H, whereby air forced back into the branches e⁵ from the cylinders F by the momentum of the car gains an easy admission into the tank H, substantially as set forth.

10 5. The combination of the steam-pipes e', air-pipe g, cocks e² g', and pump-operating cylinder D, whereby the said cylinder may be worked either by steam or by compressed air, or by both together in any desired proportion, substantially as and for the purpose set forth.

15 6. The combination of the steam-pipe e⁴,

cock e⁶, air-pipe h, cock h', and cylinders F, whereby said cylinders can be used either with steam or with compressed air, or with both combined in any desired proportion, substantially as and for the purpose described. 20

7. The combination of the propelling mechanism, consisting of cylinders F, with their respective driving, valve, and reversing connections, reservoirs C, tanks H J and their connections, and steam and air conducting, regulating, and mingling devices, substantially as and for the purpose described. 25
